US0D1002113S

(12) **United States Design Patent** (10) **Patent No.:** **US D1,002,113 S**
(45) **Date of Patent:** **** Oct. 17, 2023**

(54) **PROTECTIVE FACE MASK**

(71) Applicant: **COSMOSway Co., Ltd**, Incheon (KR)

(72) Inventor: **Kyu Sung Shim**, Incheon (KR)

(73) Assignee: **COSMOSway Co., Ltd**, Incheon (KR)

(**) Term: **15 Years**

(21) Appl. No.: **35/514,514**

(22) Filed: **Dec. 30, 2021**

(80) **Hague Agreement Data**

Int. Filing Date: **Dec. 30, 2021**

Int. Reg. No.: **DM/220225**

Int. Reg. Date: **Dec. 30, 2021**

Int. Reg. Pub. Date: **Jul. 1, 2022**

(30) **Foreign Application Priority Data**

Dec. 29, 2021 (KR) 30-2021-0062937

(51) **LOC (14) Cl.** **29-02**
